UNITED STATES PATENT OFFICE.

HARRY A. BARNES AND NELSON E. SHOWACRE, OF BALTIMORE,
MARYLAND.

COMBINED RECEIVER AND TRANSMITTER BRACKET FOR TELEPHONES.

SPECIFICATION forming part of Letters Patent No. 772,773, dated October 18, 1904.

Application filed May 6, 1904. Serial No. 206,619. (No model.)

To all whom it may concern:

Be it known that we, HARRY A. BARNES and NELSON E. SHOWACRE, citizens of the United States, residing at Baltimore city, State of Maryland, have invented certain new and useful Improvements in a Combined Receiver and Transmitter Bracket for Telephones, of which the following is a specification.

Our invention relates to a combined receiver and transmitter bracket for telephones.

One object of the invention is to provide a single bracket for supporting both the receiver and transmitter of a telephone, but which will permit the receiver and transmitter to be adjusted independently of each other to suit the operator.

Another object of the invention is to provide a construction of bracket by which the positions of the receiver and transmitter may be adjusted simultaneously or independently to suit the operator, but which will always require the operator to assume a correct position with respect to the transmitter.

Another object of the invention is to provide a construction of bracket by means of which the transmitter may be adjusted in a vertical plane and the receiver adjusted in a vertical and also a horizontal plane.

Another object of the invention is to provide a bracket of such construction as will enable an operator to use the telephone and while so doing to have the free use of both hands.

With these and other objects in view the invention is illustrated in the accompanying drawings, in which—

Figure 1 illustrates a perspective view of a telephone equipment provided with the present invention. Fig. 2 illustrates an enlarged vertical section through the center of the telephone base-board and the mechanism for operating the bell-circuit. Fig. 3 illustrates a sectional plan view of a portion of the telephone-box and a plan view of a portion of the mechanism for operating the ordinary receiver-hook, and Fig. 4 illustrates a side elevation of the receiver and a vertical section through the end of the receiver-arm and shows the details of construction by which the receiver has a lateral or yielding adjustment.

Referring to the drawings, A designates a telephone base-board provided with the usual box *a* for inclosing the mechanism now in use. These devices may be constructed in any preferred way and are merely illustrative in the drawings, it being preferred to show the invention applied to one of the usual telephone equipments now in daily use.

A bracket-plate *b* is secured to the base A in any suitable manner, and said plate is provided in the present instance with two outwardly-projecting lugs or ears *c* and a central vertical slot *c'*. A bracket *d*, in the present instance of a substantially U-shaped form, is provided with a lug *e* at its rear, which latter fits between the lugs or ears *c* on the bracket-plate *b* and is pivotally connected to said lugs by means of a suitable screw or pin *f*. This lug end of said bracket is preferably frictionally secured between the lugs, so that the outer end of the bracket may be sustained in any vertical position to which it may be moved, and the inner end of said lug is provided with a segment-rack *e'*. The bracket *d* is also provided in the present instance with two outwardly-extending arms *g* and *h*. The outer end of the arm *g* is bifurcated or slotted to form two parallel clamping-jaws *g'*, between which the supporting-arm *i* of the transmitter *j* projects and is pivotally secured by a screw *i'*.

A gear *k* is mounted in the slot *c'* of the bracket-plate *b* and meshes with the segment-rack *e'* on the inner end of the bracket-lug *e*, and this gear is mounted so as to project through a vertical slot *a'* in the base-board A. A vertical rack-bar *l* is mounted on the inner side of the base-board A, and the teeth of this rack mesh with the gear *k*. This rack-bar is sustained in its vertical position by suitable brackets *l'*, which surround it and through which the rack-bar has vertical movement. A stem *m* is also mounted on the inner side of the base-board A, and the upper end of said stem has position directly beneath the lower end of the rack-bar *l* and is provided with a yielding head *m'*, on which the lower end of said rack-bar impinges when moved downward, as will be presently described. The stem *m* is also provided at its lower end

with two horizontal arms m^2 and m^3 , which extend laterally and in a direction toward the vertical side wall of the box a , and the arm m^3 projects from the arm m^2 in a direction at 5 right angles to the stem m and has position above the usual hook-arm m^4 , now used for supporting the receiver when the phone is not in use and which serves to establish such electrical connections as will enable the bell 10 to be operated from the telephone-exchange. It is obvious that in the use of our device the hook proper on the outer end of the arm m^4 may be entirely dispensed with. A spring a^2 serves to keep the hook-arm m^4 and the 15 arms m^3 m^2 and stem m normally elevated—that is, when the rack-bar l is raised from the yielding head m' , as will be presently described.

The electrical constructions are all prefer- 20 ably made in the usual way and form no part of the invention.

The arm h of the bracket d in the present instance extends in a direction parallel with the arm g and at its outer end pivotally supports 25 an upwardly-projecting link-arm n . This link-arm is bifurcated at each end, and the lower bifurcated end n' straddles the arm h and is pivoted thereto by a pin or set-screw n^2 . The shoulder n^3 at the lower end n' of 30 said link-arm serves as a stop to limit the forward movement of said arm with respect to the arm h . The upper bifurcated end o of the link-arm n receives the inner end of the receiver-arm o' , and said receiver-arm is pivotally secured to said bifurcated end o . The 35 outer end of said receiver-arm carries a conical spring p , the larger end of which latter is attached to a receiver q . By this construction the receiver may have a universal movement when the operator's ear is pressed against it, so that the mouth of said operator may be directly in front of the transmitter. The usual wire is connected to the receiver and serves the ordinary functions.

40 By this construction and arrangement of brackets and adjustable supporting devices it will be seen that the transmitter and receiver are independently adjustable and that when adjusted to suit the operator will compel the 45 latter to talk directly into the transmitter and will leave the operator's hands free for any purpose desired.

Normally—that is, when not in speaking operation—the bracket d is pulled down, as 50 shown in Fig. 2, so that the rack-bar l will depress the stem m , the arms m^2 and m^3 , and also the hook-arm m^4 , so that the electrical conditions will be the same as when the receiver is hung on the end of the hook-arm. 55 When the bracket is thus lowered, the transmitter will have a position too low for an ordinary person while standing to talk into same.

When it is desired to use the phone, the operator will grasp the arm g of the bracket and 60 adjust the height of the transmitter to the

mouth, and this elevation of the said arm g will impart a partial rotary motion to the gear k and a vertical movement to the rack-bar l . As the rack-bar is raised from the head m' 65 the spring a^2 will raise the arm m^3 and also the hook-arm m^4 , and obviously the stem m will also be raised. This elevation of the hook-arm will establish the usual electrical circuits and put the telephone in readiness for talking. When through talking, the operator 70 will again depress the arm g and bracket, so that the rack will depress the stem and its arms and also the hook-arm.

It will be noted that the lower end of the rack is preferably unconnected to the head m' 80 or stem m and that the rack-bar may be raised a considerable distance, as might be necessary in adjusting the transmitter to the mouth of a tall person.

Having thus fully described our invention, 85 what we claim as new, and desire to secure by Letters Patent, is—

1. A telephone having signal mechanism in combination with a vertically - movable bracket; a receiver and transmitter sustained 90 by said bracket and movable therewith; a movable switch-arm to establish and maintain a distant signal after the bracket is elevated and to break the said connection when the bracket is lowered.

2. A telephone having signal mechanism in combination with a vertically - movable bracket pivoted at one end; a transmitter sustained by and movable with said bracket; a movable switch-arm below the pivoted end of 100 said bracket and arranged to maintain a distant signaling connection while the bracket is elevated and to break said connection while the bracket is lowered, and means extending from the pivoted bracket down to the switch-arm for operating the latter.

3. A telephone having a base-board provided with a box for inclosing signal mechanism, in combination with a bracket pivoted so as to move vertically above said signal mechanism; a receiver and transmitter carried by 110 said bracket; a switch-arm in said box beneath the pivoted bracket; lever mechanism extending from the pivoted bracket down to the switch-arm, and means whereby when the pivoted bracket has been elevated the switch-arm 115 will move to and be maintained in the signaling position until the bracket is lowered.

4. A telephone having a base-board provided with a box for inclosing signal mechanism in combination with a bracket pivotally mounted on said board above said signal mechanism and provided at said pivoted end with a segment-rack; a switch-arm in said box beneath the pivoted bracket; lever mechanism 120 for operating said switch-arm; a rack-bar for operating said lever mechanism, and a gear interposed between the pivoted bracket and the rack-bar for operating the latter.

5. A telephone having signal mechanism, in 130

combination with **U**-shaped bracket pivotally mounted above said signal mechanism; a receiver sustained by one of the arms of said bracket; a transmitter sustained by the other 5 arm of said bracket; a vertically - movable switch-arm beneath said pivoted bracket, and means coacting between the bracket and the switch-arm for holding the latter down when the bracket is depressed and permitting said 10 arm to maintain a distant-signaling connection while the bracket is elevated.

6. In a telephone the combination with a **U**-shaped bracket provided with outwardly-projecting parallel arms and an inwardly-projecting lug provided with a segment-rack, of a receiver sustained by one of said arms and arranged to be adjusted both in a vertical and a horizontal plane independently of said bracket-arm; a transmitter sustained by the 20 other arm of said bracket and movable in a vertical plane therewith; signal mechanism beneath said bracket; a switch-arm arranged to be moved to and maintained in a distant-signaling position when the bracket is in one 25 position; a rack-bar operated by means of the segment-gear on the lug of said bracket, and means interposed between the rack-bar and the switch-arm for operating the latter.

7. In a telephone the combination with a 30 pivoted **U**-shaped bracket having two parallel arms rigid with respect to each other; an up-

wardly-projecting arm pivotally connected to one of said bracket-arms and projecting above the same; a receiver-arm pivotally connected to the upper end of said upwardly-projecting 35 arm; a receiver supported by the said receiver-arm and having a yielding connection with the latter; a transmitter pivotally supported at the outer end of the other arm of said bracket; a signal-switch arm below said 40 bracket, and means connecting the switch-arm with the **U**-shaped bracket whereby to move them simultaneously in the same direction.

8. A telephone having signal mechanism 45 in combination with a vertically - movable bracket; a receiver sustained by said bracket; a transmitter also sustained by said bracket; a switch-arm to operate the signal mechanism; means interposed between the movable 50 bracket and said switch-arm for operating the latter to maintain a distant-signal position and means whereby the switch-arm may be independently operated to repeat the signal while the bracket is elevated.

In testimony whereof we affix our signatures in presence of two witnesses.
